UNITED STATES PATENT OFFICE.

ORLA H. WATKINS, OF CLINTON, IOWA, ASSIGNOR TO J. K. MILNER & CO.,
OF SAME PLACE.

END-GATE.

SPECIFICATION forming part of Letters Patent No. 645,241, dated March 13, 1900.

Application filed January 23, 1900. Serial No. 2,528. (No model.)

To all whom it may concern:

Be it known that I, ORLA H. WATKINS, a citizen of the United States, residing at Clinton, in the county of Clinton and State of Iowa, have invented a new and useful End-Gate, of which the following is a specification.

The invention relates to improvements in end-gates.

The object of the present invention is to improve the construction of end-gates for wagon-bodies, more especially the means for connecting the end-gates to the sides of the wagon-body, and to enable the former to be securely locked in a vertical position and to be arranged in approximately a horizontal position to form a shoveling-board and also to be hinged at the top and freed at the bottom to permit the latter to swing outward, so that the contents of the wagon-body may pass beneath the end-gate.

The invention consists in the construction and novel combination and arrangement of parts hereinafter fully described, illustrated in the accompanying drawings, and pointed out in the claims hereto appended.

In the drawings, Figure 1 is a perspective view of a portion of an end-gate and a wagon-body constructed in accordance with this invention. Fig. 2 is a plan view of one side of the wagon-body, showing the end-gate in a vertical position. Fig. 3 is a vertical sectional view, the parts being arranged in the position illustrated in Fig. 2. Fig. 4 is a horizontal sectional view of the same. Fig. 5 is a vertical sectional view, the end-gate being arranged for dumping.

Like numerals of reference designate corresponding parts in all the figures of the drawings.

1 designates a wagon body or bed designed to be provided at the inner face of each side 2 with vertical cleats 3, forming a way for a slide 4, consisting of a wooden bar and provided with an angle-iron bar 5. The angle-iron bar 5 has one of its sides or flanges secured to the inner or front face of the slide 4, as clearly illustrated in Figs. 2 and 4 of the accompanying drawings, and the other side or flange of the angle-bar is offset from

the slide 4 and arranged contiguous to the 50 adjacent side edge of an end-gate 6. The space between the offset side or flange of the angle-bar and the slide 4 receives a lever 7 and a link 8, pivoted together at 9 and similarly connected with the slide and with the 55 end-gate. The offset side or flange of the angle-bar is provided with upper and lower slots 10 and 11, receiving upper and lower studs or projections 12 and 13 of the end-gate 6, the studs or projections being preferably headed, 60 as clearly illustrated in Fig. 1 of the accompanying drawings. The lower slot is inclined and forms an open bearing for the lower stud or projection, which forms a pintle for the end-gate when the latter is swung downward. 65 to the position illustrated in Fig. 1 to provide a shoveling-board. The upperslot is vertical and is provided with a narrow entrance of sufficient width to permit the shank or stem of the headed stud or projection to pass 70 through it when the end-gate is swung downward to form a shoveling-board and when it is returned to a vertical position.

The lever 7 is provided with an ear 14, extending from one end of it at right angles and 75 pivoted to an ear 15 of the slide 4 by a rivet 16 or other suitable fastening device, whereby the lever is fulcrumed on the slide 4. The link, which is fulcrumed on the end-gate by a pivot 17, is provided with a perforated ear 80 arranged similar to that of the lever and receiving the pivot 17. When the lever and the link are arranged together, as illustrated in Fig. 3 of the accompanying drawings, they operate as a bell-crank lever and are held 85 together by lips 18 and 19, located near the fulcrum-point and arranged, respectively, at opposite sides of the lever and the link. The lip 18 of the lever is shorter than the lip 19 and extends laterally a sufficient distance to 90 engage the edge of the link, and the lip 19 of the latter is elongated and extends over the face of the lever, as illustrated in Fig. 3 of the drawings. The ear of the slide 4 is arranged approximately at the center thereof, 95 and when the lever is swung downward to a vertical position its short arm, formed by its ear, is arranged back of the fulcrum, where-

by the end-gate is securely locked against outward movement. The outer end of the lever is provided with a laterally-extending flange 20, which engages the link at the upper edge thereof when the end-gate is arranged in a horizontal or slightly-inclined position, as shown in Fig. 1, and it prevents the joint from breaking inward or downward and forms a solid brace of the link and the lever.

When the end-gate is in a vertical position, as shown in Fig. 3, the lever and the link are adapted to be swung upward to within a short distance of the top of the end-gate to permit the latter to swing downward; but by swinging the lever upward to the position shown in Fig. 5 the upper headed stud or projection is carried above the entrance of the slot 12 by the action of the said lever, its short arm or ear being arranged in an inclined position and being adapted to lift the end-gate slightly to lock the upper lug or projection 10 in the slot and to free the lower stud or projection 11 from the lower slot or bearing 13 to permit the end-gate to swing outward to dump the contents of the wagon-body. The lever is locked in this position by a pivoted hook 21, mounted on the upper portion of the offset side or flange of the angle-bar of the slide 4 and adapted to engage a notch or recess 22 of the latter. When the parts are arranged in this position, the pivot 9, which connects the link to the lever, forms the pintle of the end-gate and sustains the latter.

The end-gate is provided at opposite sides with the usual wings, and it may be constructed in any suitable manner, the headed studs or projections being preferably mounted on plates, as illustrated in Fig. 1 of the drawings.

When the lever is locked by the hook 21, the end-gate will be held in position by the same; but the upper slot and the upper headed stud or projection prevent the end-gate from swinging outward while the levers are being swung upward to such elevated position.

It will be seen that the end-gate is adapted to be readily arranged to form a shoveling-board and to permit the contents of the wagon-body to be dumped or discharged beneath it and that the lever and the link operate to lock the end-gate securely in its closed position and that the pivot which connects them forms the pintle on which the end-gate swings when the same is arranged for dumping. It will also be apparent that the upper slot and the headed stud or projection prevent the upper portion of the end-gate from swinging outward beyond the wagon-body when the lever is swung upward to free the lower end of the end-gate and to arrange the same for dumping.

Changes in the form, proportion, size, and the minor details of construction within the

scope of the appended claims may be resorted to without departing from the spirit or sacrificing any of the advantages of this invention.

What is claimed is—

1. In a device of the class described, the combination with a wagon-body provided at its bottom with an open bearing and having a slot at its top, of an end-gate having studs or projections arranged to engage the said open bearing and slot, a link pivoted at its inner end to the end-gate, a lever fulcrumed at its inner end on the wagon-body and pivotally connected to the outer end of the link, and means for locking the lever against outward movement when it is swung upward, whereby the end-gate will be lifted out of the lower bearing and will be supported by the pivot at the outer end of the link, substantially as described.

2. In a device of the class described, the combination with a wagon-body provided with an open bearing at its bottom and having a slot at its upper portion, of an end-gate provided with studs or projections for engaging the open bearing and the slot, a link pivoted to the end-gate, and a lever fulcrumed on the wagon-body and pivotally connected at a point between its ends to the link, said lever and link being provided at their inner ends with lips located at the opposite edges of the parts when their inner ends are together, substantially as and for the purpose described.

3. In a device of the class described, the combination of a wagon-body provided with an open bearing at its bottom and having a slot at its top, an end-gate having upper and lower studs or projections arranged to engage the bearing and the slot, a link provided at its inner end with an ear pivoted to the end-gate, a lever having an angularly-disposed ear at its inner end fulcrumed on the wagon-body, said lever being pivotally connected to the link at the outer end thereof, and a locking device arranged to engage the lever when the same is swung upward to the top of the wagon-body, substantially as described.

4. In a device of the class described, the combination of a wagon-body provided with ways, a slide arranged in the ways and having an offset flange provided with a lower open bearing and an upper slot, an end-gate having upper and lower studs or projections arranged to engage the open bearing and the slot, a link pivoted at one end to the end-gate, a lever pivoted between its ends to the other end of the link and fulcrumed at its inner end on the slide, and means for locking the lever when the same is swung upward to the top of the wagon-body, substantially as described.

5. In a device of the class described, the combination of a wagon-body having an upper slot and a lower bearing, an end-gate having studs or projections for engaging the slot and bearing, a lever fulcrumed on the wagon-body and provided at its inner and outer ends with

5 lips or projections, the inner end of the lever being also provided with a perforated ear arranged at an angle, and a link pivoted at one end to the lever, at a point between the ends thereof, the other end of the link being provided with an ear, and a lip and being pivoted to the end-gate, substantially as described.

In testimony that I claim the foregoing as my own I have hereto affixed my signature in 10 the presence of two witnesses.

ORLA H. WATKINS.
